UNITED STATES PATENT OFFICE.

MAUD DALITZ, OF CLEVELAND, OHIO.

SAFETY-POCKET.

1,183,800.

Specification of Letters Patent. Patented May 16, 1916.

Application filed June 1, 1915. Serial No. 31,389.

To all whom it may concern:

Be it known that I, MAUD DALITZ, a citizen of the United States, residing at Cleveland, in the county of Cuyahoga and State of Ohio, have invented certain new and useful Improvements in Safety-Pockets, of which the following is a specification.

This invention relates to a safety pocket for women and children, and the object of 10 the invention is to supply a need with both women and children for a comparatively small independent pocket, which can be attached here or there to their garments, and preferably in an unexposed and unnoticeable 15 position on an inside garment or in the inside of an outer garment, and of a size adapted to carry money and other small articles which should have a safe place on the person. Ladies find one or more of such pockets 20 desirable, as for example, a pocket attached to an inside garment to carry jewelry or other small articles of value and another hidden about the person but within reach to carry bills either for shopping or traveling, 25 as well as for other articles and uses, while small inexpensive pockets are desirable for children to care for small change and which can be pinned in convenient but unobserved places.

30 To these ends the invention consists in a safety pocket constructed and adapted to be used substantially as shown and described and particularly pointed out in the claims.

In the accompanying drawings, Figure 1 35 is a front elevation and Fig. 2 a rear elevation of the pocket. Fig. 3 is a central sectional view on line 3—3, Fig. 1, showing the flap partially raised. Fig. 4 is a detail of the supporting strip or piece adapted to 40 stretch and support the back of the pocket, and Fig. 5 is a longitudinal section of said strip with a pin attached. Fig. 6 is a cross section of the pocket looking down on line 6—6, Fig. 3, but with the pin open.

45 In the present construction P represents the pocket as such and apart from its accessories. The said pocket is necessarily made of flexible material and preferably of a suitable, heavy woven fabric to give it strength 50 and durability and to make it washable, but a lighter fabric with more or less lining can be used, or even a flexible grade of leather. However a textile pocket is preferred and which may be of any suitable or preferred 55 color and of any preferred style and size. In respect to size, I find that a pocket hav-

ing about the size shown in the original drawings herewith, or say about three inches each way, is a popular size for general use. The sides are preferably of bellows shape to 60 afford inside room, and the flap 2 is provided in this instance with a snap button 3 on the body of the pocket. An inside pocket 4 may also be provided as seen in Figs. 3 and 6. But a fabric pocket of this kind, even with 65 a pin and without a medium to stretch it laterally and to serve as a suspensory support would be found undesirable and uncommercial, and hence the invention comprises the pocket with a fairly rigid strip, 70 plate or piece 5 incorporated with the back and top thereof practically as shown and with the advantage of keeping the top of the pocket in such shape as if it were rigid while 75 all the remainder of the pocket is soft and pliable. In this instance I show a strip of metal, say of brass or aluminum, and extending entirely across the pocket from side to side and stitched about its edges and ends between the double thicknesses of the material at the back of the pocket. This 80 encloses the said strip or piece within the folds of the pocket and covers the ends for protection as well as affording a stretching suspensory medium for the pocket and by 85 which the shape thereof is maintained however flimsy the stock apart from said strip. The pocket is also practically held open thereby as the said strip comes up to the top of the edge thereof at the base of the flap. 90 The said strip 5, in the present form of the invention being of sheet metal, I am enabled to strike the ears a up therefrom to support the pin 6; the bridge b to afford a spring fulcrum for the pin and catch c to engage 95 the extremity of the pin. The said pin is of spring metal and is pivoted in or by said ears in any suitable way and adapted to be bent over the bridge or stud b as a fulcrum to cause the pin to hold under or in the 100 catch c. This, I find, provides simple and effective supporting and attaching means for the pocket, and small holes are made in the back of the pocket to enable the projections a, b and c to protrude.

105 From the foregoing it will be seen that especial stress is laid upon the transverse stretching and carrying piece for the pocket and as the base for the pin 6. Of course the material out of which said piece may be 110 made and the shape thereof are not material in a patentable sense, but in any case the

pin must be connected therewith at one end and adapted to spring beneath the catch *c* in holding relation at its other end. Having these features along its top, it matters little 5 of what material the pocket may be made except that it fall within the flexible limitations above defined. Obviously a rigid embodiment is not within this conception of pocket and a variously serviceable article at 10 a comparatively low cost of production and sale is in view.

What I claim is:—

1. A new article of manufacture consisting of a pocket of flexible material having a 15 transverse opening in its top and a back portion with a flap adapted to close over said opening, and a transversely disposed substantially rigid reinforcing piece fixed to the said back portion at the top and rear of said 20 opening and at the base of said flap, pro-

vided with rearward projections on its end portions, and a pin on the outside of said reinforcing piece and at the back of said pocket engaged with said projections and adapted to fasten the pocket in place on a 25 garment.

2. A pocket as described consisting of flexible material and having an opening in its top and provided with a plurality of holes through its back near the top thereof, 30 and a transversely disposed approximately rigid bracing piece fixed in said back and having integral projections near its ends extending through said holes, and a pin engaged with said projections.

In testimony whereof I affix my signature in presence of a witness.

MAUD DALITZ.
